Jones, Cushington, Ames & Seibold
Atty's

UNITED STATES PATENT OFFICE.

HENRY FELIX GASTON, OF CHICAGO, ILLINOIS, ASSIGNEE TO CONTINENTAL CEMENT
TILE COMPANY, OF CHICAGO, ILLINOIS, A CORPORATION OF DELAWARE.

EXTENSIBLE MOLD.

Application filed March 21, 1921. Serial No. 454,023.

To all whom it may concern:

Be it known that I, HENRY FELIX GASTON, a citizen of the United States, residing at Chicago, in the county of Cook and State of Illinois, have invented new and useful Improvements in Extensible Molds, of which the following is a full, clear, concise, and exact description, reference being had to the accompanying drawing, forming a part of this specification.

My invention relates to extensible molds that are employed for the casting of cement tiles of different lengths. My invention has special reference to a mold of the character indicated whereby tiles of cement or similar material and of different length, but having peripheral flanges to form hollow channel-like slabs closed at both ends may be economically and conveniently manufactured.

By means of my present invention, I provide an improved mold that may be utilized in manufacturing cement tiles which may be employed generally for roofing purposes. As is well known, cement tiles adapted for roofing purposes are supported on purlins which are comprised in the skeleton structure or frame-work of the building. The distances between purlins in frame-works are by no means standard and vary according to the structures of which the purlins form a part. Therefore, in order to manufacture channel-like closed end roofing tiles for the different spacings between purlins it has heretofore been necessary to have a separate mold for each length of tile. It is, of course, obvious that it is economical to use as long a tile as is compatible with good design and safety because fewer purlins are then required in the roof frame-work of the building.

By means of my improved mold, I am able to manufacture tiles of different lengths from the same mold which is capable of adjustment to permit of the casting therein of a tile of any predetermined length.

It has been the desideratum of tile manufacturers to provide hollow, channel-like tiles having closed ends, inasmuch as such a closed-end tile is capable of resisting greater dead weight and is not likely to be damaged during the handling thereof. By means of my extensible mold I am able to conveniently and economically manufacture closed-end channel-like slabs or tiles of different lengths.

In order to accomplish the foregoing ob-

jects and other objects that will be herein-after apparent, I have invented an extensible mold of the general type shown in the accompanying drawings and described in the following specification to which reference may now be had for a more complete understanding of my invention.

Fig. 1 is a plan view of an extensible mold embodying a form of my invention;

Fig. 2 is a contracted and longitudinal cross-sectional view taken along the line 2—2 of Fig. 1;

Fig. 3 is a transverse sectional view taken along the line 3—3 of Fig. 1;

Fig. 4 is a view in perspective of a closed-end channel-like slab or tile which is cast in a mold of the character shown in Fig. 1; and

Fig. 5 is a view showing how two molds embodying a form of my invention may be positioned side-by-side so as to permit of the simultaneous casting of two closed-end channel-like slabs or tiles of the character illustrated in Fig. 4.

The extensible mold of Figs. 1, 2 and 3 comprises two body portions 1 and 2, each of which is provided with a central expanded elevation which is flanked on two sides and one of its ends by means of laterally extending flange portions 3. The body members 1 and 2, are placed end-to-end, their open ends, as shown in Fig. 2, being opposed to each other. These body members are adapted to telescope within each other whereby the elevated expanded portions of both body members merge into each other to form one continuous central elevation for the mold as shown particularly in Fig. 3. Similarly, the flange portions 3 formed at the sides of the body members 1 and 2 merge into each other and, in conjunction with the flange portions 3 formed on the outer ends of the body members 1 and 2, form a continuous peripheral flange for the above mentioned central elevation of the mold.

In setting up the mold, the two scoop-shaped body portions 1 and 2 are placed upon angle-irons 4 and 5 as shown in Fig. 3, the flange portions 6 of the angle irons subtending the horizontal flanges 3 of the body members 1 and 2. At the ends of the mold, angle-irons 7 and 8 are disposed, as shown in Fig. 2, the horizontal flanges 9 thereof resting upon the flange

portions 3 formed at the ends of the body members 1 and 2. In this fashion a peripheral trough 10 is formed in the mold which completely surrounds the central elevation of the mold on both of its sides as well as its two ends. The angle-iron side members 4 and 5 and the angle-iron end members 7 and 8, when properly positioned relative to the flange portions 3 of the body members 1 and 2, are held in position by means of clamps 11 or any other suitable devices. Each of the body members 1 and 2 is reinforced at its expanded or arched portion by means of channel irons 12 that extend transversely of the mold as shown in Fig. 2.

After the mold is assembled, the two body members 1 and 2 being telescoped to the proper degree, depending upon the length 20 of the tile desired, cement or other suitable material is poured into the mold. When this material has become properly set the mold is emptied of its contents and a closed-end channel-like slab of tile, of the general 25 form illustrated in Fig. 4 is the result.

By referring to Fig. 4 it will be noted that the tile comprises a central hollow portion 13 that is flanked on its sides by the walls 14 and on its ends by the end walls 15. It will, therefore, be observed that the 30 hollow tile of Fig. 4 is a product resulting from the mold hereinbefore described. It is also obvious that tiles similar to that shown in Fig. 4, but of different lengths, may be 35 cast in a mold constructed in accordance with my invention, since the body members 1 and 2 are capable of being telescoped to accord with the length of tile desired.

When it is desired to simultaneously cast 40 several channel-like slabs or tiles in molds embodying a form of my invention, mold sections 16 and 171 may be arranged side by side as shown in Fig. 5. In this instance, an inverted T-shaped iron 18 is placed between the two mold sections, the flanges 3 thereof resting upon the base of the T. The 45 T-iron 18, therefore, forms a single side member or wall for a compound mold and is common to both mold sections.

While I have described herein one form 50 of my invention it is understood that I do not desire to have any limitation imposed thereupon except as specifically set forth in the appended claims, or required by the 55 prior art, since mechanical expedients or equivalents of the various elements of my

mold may be evolved which come within the scope of my invention.

Having thus described my invention what I now claim as new and desire to secure by 60 Letters Patent is:

1. An extensible mold for casting closed-end channel-like slabs which comprises two pairs of spaced substantially parallel angle-irons arranged in the form of a parallelogram having facing horizontal flanges and upstanding web-portions, and two inverted scoop-shaped body members disposed end-to-end and adapted to telescope within each other, said body members being severally 70 provided with laterally extending portions along the edges of their sides and exposed ends, said laterally extending portions overlapping said flanges and forming together with said body members and web-portions 75 a peripheral trough around the mold.

2. An extensible mold for casting channel-like slabs which comprises two spaced substantially parallel angle-irons having facing flanges, two facing inverted scoop-shaped 80 body members telescopically slidable together along said flanges, and angle-irons resting upon the exposed ends of said body members transversely of and between said first named angle-irons, said angle-irons 85 serving to form with said body members a continuous trough around the periphery of the mold.

3. An extensible mold for casting closed-end channel-like slabs which comprises two 90 pairs of spaced substantially parallel angle-irons arranged in the form of a parallelogram and having facing horizontal flanges and upstanding web-portions, and two inverted scoop-shaped body members disposed 95 end-to-end and adapted to telescope within each other, said body members being severally provided with laterally extending portions along the edges of their sides and exposed ends, said portions being of a width 100 substantially equal to the width of said horizontal flanges and said portions fully overlapping said flanges thereby forming together with said body members and web-portions a peripheral trough of predetermined 105 dimensions around the mold.

In witness whereof, I have hereunto subscribed my name.

HENRY FELIX GASTON.
